(57) **CLAIM**

The ornamental design for a flat tire repair kit, as shown and described.

DESCRIPTION

FIG. 1 is a front perspective view of the flat tire repair kit, according to the invention;

FIG. 2 is a front view of the flat tire repair kit shown in FIG. 1;

FIG. 3 is a rear view of the flat tire repair kit shown in FIG. 1;

FIG. 4 is a top view of the flat tire repair kit shown in FIG. 1;

FIG. 5 is a bottom view of the flat tire repair kit shown in FIG. 1;

FIG. 6 is a side view of the flat tire repair kit shown in FIG. 1;

FIG. 7 is a side view, opposite the side view shown in FIG. 6, of the flat tire repair kit shown in FIG. 1; and,

FIG. 8 is a front perspective view, opposite the view shown in FIG. 1, of the flat tire repair kit.

The broken lines depict portions of the flat tire repair kit that form no part of the claimed design.

1 Claim, 8 Drawing Sheets
